UNITED STATES PATENT OFFICE.

JOHN EDGAR TURNER, OF MCCLURE, VIRGINIA.

INKWELL.

Application filed September 12, 1921. Serial No. 500,044.

To all whom it may concern:

Be it known that I, JOHN E. TURNER, a citizen of the United States, and a resident of McClure, in the county of Dickenson and State of Virginia, have invented a new and useful Improvement in Inkwells, of which the following is a full, clear, and exact description.

My invention relates to ink wells, and it consists in the combinations, constructions, and arrangements herein described and claimed.

An object of my invention is to provide an ink well having a cover for an ink reservoir therein movably connected with a pen holding rack, whereby the cover will be moved into closed position when a pen is placed on the rack and will be moved into open position when the pen is removed from the rack.

A further object of my invention is to provide a device of the character described that is simple in construction and can be manufactured cheaply.

Other objects and advantages will appear in the following specification, and the novel features of the invention will be particularly pointed out in the appended claims.

My invention is illustrated in the accompanying drawings forming part of this application, in which—

Figure 1 is a front elevation of the device, portions thereof being broken away and other portions being shown in section,

Figure 2 is a top plan view of the device, portions thereof being broken away, and

Figure 3 is a section along the line 3—3 of Figure 2.

In carrying out my invention, I provide a body portion 1 of general rectangular shape, as clearly shown in the drawings. The body portion 1 may be formed of glass, metal, or any other suitable material and is fashioned with an upstanding integral extension 2 along its rear edge, which has the form of a plate, as best seen in Figure 1. The extension 2 is fashioned with a plurality of slots 3 extending vertically from the upper edge thereof to the upper face of the body portion 1. The slots 3 have their greatest width at their upper ends and are then reduced in width uniformly for approximately half of their height, being uniform in width from that point to their lower ends. A pair of vertical

rack plates 4—4 are counter-sunk in opposite faces of the plate 2 in position to extend across the lower portion of each slot 3 and are provided with oppositely extending ears 5—5 which are attached to the plate 2 by means of bolts 6 or like fastening means. The plates 4 are provided with alined angular grooves or recesses 7—7 in their upper ends in which a pen holder 8 may be disposed. A stub shaft 9 is journaled in the plates 4—4 adjacent to their lower ends and carries a pinion 10 which is in mesh with the teeth 11 on the upper face of a disk portion 12 of an arm 13. The disk portion 12 of the arm 13 is rotatably mounted on a vertical shaft 14 fast in a recess 15 in the upper face of the body portion 1. The arm 13 is entirely disposed in the recess 15 and can be moved pivotally therein about the axis of the vertical shaft 14. The arm 13 is formed integrally with or is rigidly connected to a cover 16 for a vertical chamber 17 which is communicatively connected at its lower end by a passage 18 with the main reservoir 19 which is formed in the body portion 1, as shown. The reservoir 19 has a filler opening 20 for which a cover 21 is provided.

The shaft 9 carries an arm 22 which extends above the upper ends of the plates 4—4 and is curved to conform with the curvature of a side wall of the slot 3. A V-shaped spring member 23 is disposed in the slot 3 at its lower end with one arm 24 thereof contacting one wall of the slot 3 and its other arm 25 reacting against the arm 22 and tending to swing the latter from the position indicated by the full lines in Figure 1 into the position indicated by the dotted lines in the same figure. It will be manifest that such a movement of the arm 22 will rotate the pinion 10 and in consequence the arm 13 will be moved within the recess 15 from the position indicated by the full lines in Figure 2 into the position indicated by the dotted lines in the same figure. The cover 16, which is integral with the arm 13 or rigidly secured thereto, will likewise be moved in the recess 15 and the compartment or chamber 17 will be uncovered.

From the foregoing description of the various parts of the device, the operation thereof may be readily understood. When a pen holder is moved downwardly in the slot 3 against the action of the spring 23 to rest on

the upper ends of the plates 4—4, the arm 22 will be maintained in the position indicated by the full lines in Figure 1 and the ink chamber or compartment 17 will be closed, thereby preventing the evaporation of the ink therefrom and preventing dust and the like from falling into the chamber. When it is desired to use the pen, the pen holder is grasped and removed from the slot 3. The 10 arm 22 is then moved into the position indicated by the dotted lines in Figure 1 by action of the spring 23 and the cover 16 is moved laterally of the open upper end of the chamber 17 in the manner described.

15 A cover plate 26 is superposed on the upper face of the body portion 1 and is fashioned with a relatively raised or vertically offset portion 27 adapted to overlie the pinion 10 and the gear disk 12, whereby these 20 parts are housed without there being any interference with the operation thereof. The cover plate 26 is formed with a cavity 28 therein in which pen points, paper clips, pins, and the like may be placed.

25 It will be observed that the ink well embodying my invention has the general appearance of an ink well of ordinary construction and is adapted for all uses to which an ordinary ink well may be put. In addition, 30 a great economy is effected in that the ink in the chamber 17 is kept free from dust and the chamber 17 is covered at all times except when ink is being taken therefrom. An opening 29 is provided in the cover plate 26 35 to permit access to the chamber 17 when the cover 16 has been displaced.

I claim:

40 1. An ink well comprising a substantially rectangular body portion formed with an ink holding reservoir in its upper side and with a vertical extension along one edge, said extension being fashioned with a vertically extending slot therein, a cover for the reservoir, a pair of vertical plates at-

tached to opposite sides of the extension in 45 position to close the lower portion of the slot, a horizontal shaft journalled in the plates adjacent to the lower end of the slot, a pinion carried by the shaft, an arm rigidly secured at one end to said cover and fashioned 50 at its other end to provide a disk portion, said disk portion being provided with a series of gear teeth on one face thereof, means for pivotally attaching said disk portion to the body portion to cause said teeth to mesh 55 with said pinion, an arm upstanding in the slot above the level of the plates, said arm being rigidly secured at its lower end to said horizontal shaft and being curved to conform with one wall of said slot, and 60 spring means disposed in said slot and reacting against said upstanding arm to yieldingly hold it against the wall of the recess opposite the first mentioned wall.

2. An ink well comprising a frame having 65 an ink reservoir therein and a compartment in communication with said reservoir, a cover adapted to close the top of said compartment, a plate disposed over said reservoir and cover, and having an opening in 70 registration with said compartment, and means for moving said cover into closed position, said means being adapted to grip a pen and being actuated when a pen is disposed therein, said means also being adapted 75 to move said cover into opened position when the pen is removed therefrom.

3. An ink well comprising a body portion formed with an extension having a pen receiving slot therein, said body having an 80 ink reservoir therein, an arm disposed in said slot and being moved when a pen is disposed in the slot, a cover for said reservoir, and a pinion operatively connecting said arm to said cover, whereby said cover will 85 be moved into closed position when a pen is disposed in said slot.

JOHN EDGAR TURNER.
